DISCHARGE DEVICE

Charles C. Neas, Boston, Mass., assignor to the
United States of America as represented by the
Secretary of the Navy

Application September 14, 1945, Serial No. 616,387

3 Claims. (Cl. 62—1)

1

This invention relates to liquefied gas containers and is illustrated herein as embodied in a discharge device for effecting the adiabatic removal of the contents of a liquefied gas container.

It is well known that in any attempt to obtain nearly complete adiabatic discharge of cylinders of liquefied gases such as N_2O or CO_2 , it is necessary to remove the cylinder contents as liquid. Otherwise, if a predominantly gaseous discharge occurs, the heat of vaporization given up by the remaining liquid will cool it thus reducing its vapor pressure and removing the driving pressure necessary to eject the gases.

In the ordinary use of liquefied gas, the container may be held in an upright position, and a discharge of the contents in a liquid state is effected by a dip pipe with openings adjacent to the bottom of the gas container. However, in several applications, such as life raft inflation and carbon dioxide fire extinguishers, the position of the cylinder during discharge cannot be controlled or predicted so as to insure a liquid discharge upon opening the release valve. If the usual type of container is inverted the discharge will be entirely gaseous with the undesirable results noted above; and in the inflation of a life raft a serious delay would ensue.

In the operation of aircraft over cold waters, it is necessary to have quick inflation of life rafts in order to avoid fatal exposure of personnel to cold water.

The airplane life rafts of particular interest in connection with this invention are the larger ones of the automatic type. These rafts are stored in compartments in various positions in the fuselage and may be ejected in such a manner that a raft, with its associated gas container, turns end over end while being ejected and inflated. When on the surface of the water the raft may float with either side up. Thus, the position of the liquefied gas container is variable and unpredictable for any stage of the period of the discharge.

At high altitudes temperatures as low as $-65^\circ F$. are encountered; and, during a flight of from 10 to 12 hours at those temperatures, a life raft and cylinder may be cooled to temperatures of $-40^\circ F$. or lower, whereby the vapor pressure inside the cylinder is reduced and the time required to inflate the raft completely is increased. It is desirable to have as little exposure of personnel to the water as possible and even to have the raft fully inflated in the thirty seconds during which a ditched airplane may sink to permit oc-

cupants of the airplane to step directly from the plane to the raft without becoming wet.

With ordinary containers, it is not possible to get a satisfactorily complete and rapid discharge, particularly with a gas container at a low temperature, to inflate a raft before the plane sinks, for, with a container in certain positions, an entirely gaseous discharge is obtained and the liquid remaining in the container after partial discharge is cooled sufficiently to slow the discharge.

Therefore, it is a principal object of this invention to provide for the rapid and complete removal of liquefied gases in a predominantly liquid state from a container in which they are stored, under high pressure, regardless of the position of the container.

To this end, the invention provides an improved discharge device for a liquefied gas container which includes, instead of the usual dip pipe referred to above, a tube which extends from one end of the container longitudinally thereof substantially to its other end, the tube having openings adjacent to both of its ends. Accordingly, when the container is in any other-than-horizontal position at least one opening in the tube will be immersed so long as the discharge of the container is not nearly completed.

In order to insure the complete discharge of the container when it is disposed horizontally or in other tilted positions the invention further provides as another feature thereof, a flexible terminal section on the tube which is adapted to swing, under the influence of the force of gravity, close to or into engagement with whatever part of the container wall is lowest. One or more openings adjacent to the end of the flexible section are thus disposed at nearly the lowest point in the liquid when the container is horizontal or in any tilted position above the horizontal position.

When a discharge tube constructed in accordance with this invention is employed to remove the contents of a container of liquefied gas, at least some of the openings therein are below the liquid surface regardless of the position of the container and at least a part of the contents are removed as liquid throughout the entire period of the discharge.

With the above and other features and objects in view, the invention will now be described with reference to the accompanying drawing which illustrates a preferred embodiment of the invention and will be pointed out in the claims.

The figure is a side elevational view showing the discharge tube in place in a cylinder for containing liquefied gas, the cylinder and part of the

discharge tube being shown in section. The position of the tip of the tube when the cylinder is upright is shown in dotted lines.

As illustrated in the drawing, the liquified gas container includes a hollow body portion 1 of conventional design, the body portion being cylindrical and having a closed end 2 and an open mouth 3. A cap 4 closes the mouth 3. A T-shaped channel 5 in the cap 4 connects with the inside of the container. One free arm of the channel 5 is closed with a puncture disc 6 which may be attached to puncture mechanism associated with a life raft or other equipment (not shown). A safety disc 9 held in place by a cap 10, closes the other open arm of the channel 5.

A discharge tube 11 is located inside the container and is threaded to the cap 4. The discharge tube 11 extends longitudinally through the container coaxially therewith. The tube has a plurality of openings 12 adjacent to the mouth 3 and a further plurality of openings 13, adjacent to the closed end 2 of the container through which its contents are introduced into the discharge tube.

The greater portion of the tube 11 is constructed of rigid material, but a tip portion 14 thereof is preferably made of flexible material. The flexible tip 14 is made sufficiently long that when the axis of the container is tilted away from the vertical, the tip is pulled against the wall of the container by the force of gravity, as clearly shown in the drawing.

A cover 15 in which the openings 13 are formed is attached to the end of the flexible tip and is so constructed as to prevent the openings from coming into direct contact with, and being closed by, the side walls of the container. The lower surface of the cover 15 is cone shaped as indicated at 16 in the drawing; and as the container is tilted the flexible tip swings until the conical portion 16 of the cover rests against the lower portion of the side wall of the container as shown in the drawing. For best results, the flexible tip 14 should be sufficiently long that the cover 15 swings against the side wall of the container, the conical portion 16 resting against the wall, as shown in the drawing, when the container is tipped. Thus the openings 13 are kept away from the wall. However, the flexible tip should not be long enough to become kinked during rough handling of the container. Accordingly, the rigid portion of the tube should extend the greater part of the length of the container.

As shown in the drawing, the openings 13 are drilled in the cover a short distance above the conical portion 16. When the container is vertical, the openings 13 are adjacent to the closed end 2 of the container; and when the container is horizontal, the openings 13 are adjacent to the low side of the container wall. Dotted lines indicate the position of the flexible tip when the container is in an upright position.

For best operation, the combined areas of the openings 12 should be substantially smaller than the area of the bore of the tube in order that the flow of gas through the openings 12 will create a pressure drop slightly greater than the hydrostatic head of liquid when the cylinder is upright. In other words, in the upright position of the container, the flow of gas through the openings 12 at a particular temperature of the liquified gas within the container creates a pressure differential or head between the outside and the inside of tube 11 of sufficient magnitude to force the liquid from the liquid level within the con-

tainer to the free end of T-shaped channel 5 in which puncture disc 6 is located. That is, for a predetermined temperature of the liquid in the container, the flow of gas through the openings 12, which is formed above the liquid by evaporation of the liquid, is of such an amount that the pressure head between the outside and the inside of the tube overcomes the hydrostatic head of a column of liquid within the tube extending from the liquid level within the container to the outer extremity of the channel 5. The openings 13 in the tip, on the other hand, are made large enough to permit a flow through them equal to that which the tube can accommodate. It has been determined that best results are obtained when the ratio of the combined areas of the openings 12 and the area of the bore of the tube is substantially $\frac{1}{2}$. For example, with a container charged with 3.25 pounds of liquid N_2O and cooled to -40° F. , a tube of 0.234 inch internal diameter having large openings in the tip and having two openings adjacent to the base each having a diameter of 0.116 inch, gave good results whether the container was upright or inverted. In 25 seconds, 95% or more of the container contents were discharged in each container position.

When the openings are constructed as described, a discharge containing at least some liquid is provided in any position of the container. When the openings 13 in the tip are immersed and the openings 12 in the base of the tube are above the liquid surface, the pressure drop of gas flowing through the openings 12 of the tube is sufficient to force liquid up the tube to be swept out of the cylinder in the gas stream. On the other hand, when the openings 12 of the tube are immersed, the hydrostatic head forces liquid into the tube 11 through these openings in preference to gas through the openings 13 in the tip. The flexible portion 14 of the discharge tube 11 is necessary to insure that openings are below the liquid's surface when the axis of the container is horizontal regardless of the amount of liquid therein.

This invention thus insures, regardless of container position, a discharge in which liquid is always present. Although the gaseous phase may account for the major portion of the discharge on a volume basis, nevertheless, the discharge on a weight basis is predominantly liquid because of the higher density of the liquid.

The device illustrated is particularly effective for discharge of containers of N_2O . However, it may be used satisfactorily with other gases liquified under pressure and the scope of the invention is not to be limited to use with N_2O .

Having described my invention what I claim as novel and desire to protect by Letters Patent of the United States is:

1. Apparatus for the adiabatic discharge of liquified gas under pressure from a container having a discharge cap, said apparatus comprising a tube secured to said cap and extending into said container, said tube having a rigid section and a flexible section, and a terminal member secured to said flexible section and having an opening in the side thereof near its extremity, said rigid section of said tube having openings therein adjacent to said discharge cap, the combined areas of said last-mentioned openings being of such size relative to the bore of said tube that the pressure drop of gas through said openings at the temperature of the liquified gas is greater than the hydrostatic head of a column of said

liquid within said tube extending from the liquid level within the container to said discharge cap.

2. In combination, a cylinder having a closed end and a discharge cap adapted to contain liquified gas under pressure, and a tube secured to said cap and extending into said cylinder substantially coaxial therewith, said tube being rigid for a substantial portion of its length and having a flexible section terminating adjacent to the closed end of said cylinder, said flexible section terminating in a cover having openings in the sides thereof, said rigid portion of said tube having a plurality of openings therein adjacent to said cap, the combined areas of said last-mentioned openings being of such size relative to the bore of said tube that the pressure drop of gas through said openings at the temperature of the liquified gas is greater than the hydrostatic head of a column of said liquid within said tube extending from the liquid level within the cylinder to said discharge cap.

3. Apparatus for the adiabatic discharge of liquified gas under pressure from a closed container comprising, a tube attached to the outlet of said container and extending substantially to the bottom thereof, said tube having a first plu-

rality of openings in the end thereof furthest removed from said outlet and a second plurality of openings therein adjacent said outlet, the combined area of said second plurality of openings being of such size relative to the bore of said tube that the pressure drop of gas through said openings at the temperature of the liquified gas is greater than the hydrostatic head of a column of said liquid within said tube extending from the liquid level within the container to said outlet.
